WATER-HEATER CONTROL

Salvatore Merendino, Pasadena, Calif., assignor to General Controls Co., Glendale, Calif., a corporation of California

Application July 9, 1956, Serial No. 42,169

Term of patent 14 years

(Cl. D52—1)

Fig. 1

Fig. 2

Figure 1 is a perspective view of a water-heater control embodying my new design; and

Figure 2 is an elevational view of the left side of the control not visible in Fig. 1.

The back of the control, not visible when the control is installed on a water heater, is generally the same in appearance as the front.

The essential features of the design reside in the portions shown in full lines.

I claim:

The ornamental design for a water-heater control, substantially as shown and described.
